CRIMPING DEVICE

George Poehlmann, Indianapolis, Ind., assignor to Western Electric Company, Incorporated, New York, N.Y., a corporation of New York

Filed Nov. 22, 1957, Ser. No. 698,161

3 Claims. (Cl. 153—21)

This invention relates to crimping or metal-forming devices, and more particularly to a crimping device employing a pair of rollers for simultaneously crimping two spaced rows of prongs extending from a switch assembly.

In the manufacture of one type of electrical switch, the components thereof are assembled and retained by means of two rows of spaced prongs or lugs extending from certain of the components over the other components. In order to facilitate the assembly of the switch, it is desired that a simple device be provided for simultaneously applying oppositely directed bending forces to both rows of prongs whereby the prongs will be bent toward each other to complete the assembly of the switch.

It is a prime object of this invention to provide a simple device for applying uniform bending forces to a plurality of elements extending from an article to be assembled.

It is a further object of the invention to provide a pair of crimping rollers that function to simultaneously crimp prongs extending from diverse locations on a group of components to be assembled.

Another object of the invention resides in the use of slotted blocks for guiding a pair of crimping rollers to simultaneously bend two spaced rows of prongs toward each other.

With these and other objects in view, the present invention contemplates a base and a group of springs mounted thereon to support an actuator bar in an elevated position. Depending from the bar is a pair of blocks having inverted V-shaped slots formed therein to receive and guide a pair of crimping or forming rollers. A resiliently urged member holds the rollers at the lower extremities of the slots. When a switch assembly having two spaced rows of prongs to be crimped is placed on the base and the actuator bar is manually depressed, the pair of rollers will engage the prongs and exert bending forces thereon as the rollers ride along the slots toward each other to simultaneously crimp the opposing rows of prongs toward each other.

Other objects and advantages of the present invention will be apparent from the following detailed description when considered in conjunction with the accompanying drawings, wherein

Fig. 1 is a front elevational view of a roller type crimping device embodying the principal features of the present invention;

Fig. 2 is a top plan view of the crimping device partially cut away along line 2—2 of Fig. 1 to particularly illustrate the construction of guide members;

Fig. 3 is a sectional view taken along line 3—3 of Fig. 1 depicting crimping rollers in an elevated position;

Fig. 4 is a view similar to Fig. 3 but depicting the crimping rollers in a down or crimping position, and

Fig. 5 is a perspective view of a switch having prongs crimped over by the device shown in the other views.

Referring first to Fig. 5, there is shown a switch assembly 10 crimped by the apparatus of the present invention. It will be noted that there are four prongs 11, 12, 13 and 14 extending up from a bracket component 16 which have

2

been crimped over to secure a component 17 in position. A switch assembly 10 having uncrimped prongs is loaded in a work holder 18 (Fig. 1) so that a slide button 20 thereon extends within a slot 21 formed in the work holder 18. The work holder 18 is slidably moved along a base 19 between guide bars 22 and 23 into engagement with a stop 24 extending from the base 19. A set of four springs 26 positioned on the base 19 provides support for an elongated rectangular shaped actuator bar 27. Secured

10 to and extending from the underside of the bar 27 are four stud rods 28 adapted to be positioned within the four springs 26 so that when the actuator bar is depressed the stud rods will engage the base 19 and limit downward movement of the bar 27. These rods 28 also function to preclude buckling of the springs 26. A pair of blocks 29 and 31 are also secured to the underside of the bar 27 and each has formed therein an inverted V- or heart-shaped slot 32 (see Figs. 3 and 4). Positioned within the slots 32 are two hardened steel crimping rollers 33 and 34.

20 In order to insure rectilinear movement of the blocks 29 and 31 when a pressing force is applied to the bar 26, guide facilities are provided. These guide facilities include cut-out sections 36 and 37 formed in the blocks 29 and 31 that accommodate therein a pair of complementary 25 guide members 38 and 39 secured and extending upwardly from the base 19. Spanning and constantly engaging the rollers 33 and 34 is a holding bar 41 that is continuously urged downwardly by a pair of compressed springs 42 and 43 interposed between the bar 27 and the bar 41.

30 In operation of the crimping device, a switch assembly 10 having uncrimped prongs 11—14 is loaded on the work holder so that the button 20 is positioned within the slot 21. The work holder is moved between the guide bars 22 and 23 into engagement with the stop 24 thereby 35 positioning the prongs 11—14 to be engaged by rollers 33 and 34.

A depressing force which may be either manual or power derived is applied to the bar 27 whereupon the bar 27 and the blocks 29 and 31 move downwardly. The 40 rollers 33 and 34 being continuously urged toward the bottom of the extremities of the V-shaped slots 32 engage the prongs and apply bending forces thereto. The further the bar 27 is depressed the greater will be the compression of the springs 42 and 43 so that continuously increasing bending forces will be applied to the prongs. The 45 rollers 33 and 34 will move upwardly and toward each other in the slots 32 thereby applying forces to laterally bend the prongs 11—14 toward each other and eventually over the component 17.

50 It is to be understood that the above-described arrangements of apparatus and construction of elemental parts are simply illustrative of an application of the principles of the invention and many other modifications may be made without departing from the invention.

55 What is claimed is:

1. In a metal lug-crimping device, an actuator bar, resilient means for supporting the bar in an elevated position, a pair of blocks secured to and extending downwardly from the bar, said blocks having inverted heart-shaped slots formed therein, a pair of metal-forming rollers mounted in the slots, and means for urging said rollers into the extremities of the slots.

2. A crimping device comprising a base for receiving an article to be crimped, a bar, resilient means for supporting the bar in spaced relationship with respect to the base, a pair of parallelly spaced blocks secured to and extending from the bar toward the base, each of said blocks having an inverted heart-shaped slot formed therein, a pair of crimping rollers positioned within the slots, a holding member spanning said rollers, and resilient means interposed between the holding member and the

bar for urging the crimping rollers toward the lower extremities of the slots.

3. A crimping device comprising a resiliently supported bar, a pair of blocks extending downwardly from the bar; each of said blocks having an inverted heart-shaped slot with curved and upwardly cusping surfaces formed therein; a pair of rollers positioned in the lower extremities of the curved and upwardly cusping surfaces of the slots; means for transferring a depressing force applied at the bar to the rollers whereby the rollers act against a work piece to move up and along the cusping

surfaces toward each other to accomplish a crimping action, and means for restoring the rollers to the initial position upon removal of the depressing force.
